MAGAZINE FIRE-ARM.

SPECIFICATION forming part of Letters Patent No. 400,472, dated April 2, 1889.

Application filed October 13, 1887, Serial No. 252,249. (No model.) Patented in Germany August 21, 1887, Nos. 43,431 and 43,576, and January 13, 1888, No. 43,669; in France September 22, 1887, No. 186,004; in Belgium September 22, 1887, No. 78,966; in Portugal November 9, 1887, No. 1,192; in Italy November 30, 1887, XXI, 22,334, XLIV, 111; in Spain January 2, 1888, No. 11,850; in Austria-Hungary February 17, 1888, No. 37,053 and No. 2,754, and in England September 22, 1888, No. 12,882.

To all whom it may concern:

Be it known that we, ARMAND MIEG and HUGO BISCHOFF, both subjects of the King of Bavaria, ARMAND MIEG residing at Leipsic, 5 Saxony, Germany, and HUGO BISCHOFF residing at Berlin, Prussia, Germany, have invented new and useful Improvements in Breech-Loading Fire-Arms, (for which we have obtained a patent in Austria-Hungary, 10 No. 37,053, tome 38, folio 329/2,754, tome XXII, folio 313, dated February 17, 1888; England, No. 12,882, dated September 22, 1888; Spain, No. 11,850, dated January 2, 1888; France, No. 186,004, dated September 22, 1887; 15 Belgium, No. 78,966, dated September 22, 1887; Italy, Reg. Gen. Vol. XXI, No. 22,334 / Reg. Att. Vol. XLIV, No. 111, dated November 30, 1887; Portugal, No. 1,192, dated November 9, 1887; Germany, No. 43,431, dated August 21, 1887; 20 Germany, No. 43,669, dated January 13, 1888, and Germany, No. 43,576, dated August 21, 1887,) of which the following is a specification.

This invention relates to improvements in breech-loading fire-arms, and especially to improvements in the breech, the barrel, and the repeating mechanism.

The novel features of the invention are more fully pointed out in the following specification and claims, and illustrated in the accompanying drawings, in which—

Figure 1 is a longitudinal section of the fire-arm. Fig. 1^a shows the barrel as seen from below. Fig. 2 is a vertical section in the plane x y, Fig. 1, and Fig. 2^a is a vertical section in the plane y z, Fig. 1^a. Figs. 3 to 9 show details of the breech mechanism. Figs. 10 to 18 represent the magazine and the details of the same.

In the drawings, the letter a designates the firing-pin, which is connected with a supplemental breech-bolt, S, by means of a nut, b, which is inserted into the supplemental breech-bolt and provided with two tappets, b' b'', (see Figs. 1, 4, and 5,) sunk into the front sides of the same, and thus preventing the nut from rotating.

The supplemental breech-bolt S is coupled with the firing-pin a by means of a handle, c, the inner front surface of which lies on the 50 front side of the supplemental breech-bolt S, forming thus an immovable connection between the same and the firing-pin a. The handle is in this case of an annular shape; but it may also have any other suitable form. 55

To avoid any accidents in the case of a misfire, the handle has for its purpose to cock the supplemental breech-bolt without opening the main breech-bolt V, Fig. 1. To do this the supplemental breech-bolt is simply withdrawn 60 by means of the said handle, so that it is not necessary to open the main breech-bolt. The catch is connected with the handle c, and it consists of a double-armed lever, d e, Fig. 1, which is pivoted at f between two projections 65 of the supplemental breech-bolt S. The arm e of the lever is provided with a cam, e', which fits into a corresponding recess, e², of the main breech-bolt V. The arm d is formed as a handle lying on the handle c. In the drawings the lever is shown in the disengaged position. 70

The position in which the catch is in engagement is shown in dotted lines. The cam e' of the lever catches into the recess e², and 75 thereby prevents the supplemental breech-bolt and firing-pin from moving forward toward the barrel, while at the same time the trigger-blade r is discharged, the supplemental breech-bolt being pushed back a little, 80 owing to the form of the cam e' or of the recess e². The opening of the main breech-bolt when the supplemental breech-bolt is cocked is prevented at the same time by the cam e' entering the recess e². The cocking is effected 85 by simply raising the handle d of the lever d e, while the disengagement is effected by pressing down the said handle. A small trigger-pin, f', Fig. 1, secured to the lever-arm d and catching into the handle c, serves to stop 90 the lever d e. The closing-nib g on the left side, which in opening and withdrawing the main breech-bolt V is directed downward, (see Figs. 1 and 9,) is, contrary to the hitherto

used form, dovetailed and enters a correspondingly-shaped groove of the closing-socket, (see Fig. 9,) in order to prevent any rocking movement of the breech-bolt in the closing-socket and to facilitate the working of the supplemental breech-bolt.

The repeating mechanism is constructed as follows: In front of the trigger-guard, at the under side of the stock or of the barrel, is the ¹⁰ cartridge-magazine M, in which the cartridges are arranged in an oblique position, having their pointed ends turned upward and ranged in a curve to the place where the cartridge is delivered into the barrel. A spring, *h*, of an ¹⁵ oblong form, which is rounded off at the corner and bent inward at the middle, (see Figs. 1 and 2,) acts on a follower, *i*, and forces the cartridge toward the cartridge-chamber. We have chosen this form of the spring, in order ²⁰ to reduce as much as possible the friction between the spring and the walls of the magazine. The connection between the spring *h* and the follower *i*, Fig. 1, is rendered movable by means of the plate *k*, which on one side ²⁵ receives the pressure of the spring, and on the other side is connected by a pin, *l*, with the follower *i*. The pin *l* plays in a slot in the follower, so that the latter may move in the magazine without any difficulty. As shown in ³⁰ Fig. 2, the magazine is narrower at its upper part, in order to guide the cartridge surely on its fore thinner end and to guide the spring *h*. The device for introducing the cartridges separately into the chamber consists of two compound ³⁵ pawls, *m m*, which are put in action by means of a cam, *p*, secured to a closing head-piece, *P*, Figs. 1, 10, 11, and 12. The compound pawls *m m* are fixed to movable spindles *n n*, to which are secured the levers *o o*, which ⁴⁰ when in motion rotate the spindles *n n*, and consequently move the pawls *m m*. The levers *o o*, Fig. 15, are arranged, with respect to the closing head-piece *P*, in such a manner that when the latter opens the main breech-bolt the cam *p* passes between the levers *o o* and ⁴⁵ separates the top ends of the same, and thereby oscillates the pawls *m m*. After the cam *p* has passed between the levers *o o* the latter are brought back into their former positions.

Figs. 13, 14, and 15 explain the operation of the pawls. Assuming the cartridge No. 1 to be in the chamber, from which it is introduced by the main breech-bolt into the barrel, the ⁵⁵ cartridge No. 2 is then placed between the pawls *m m* and held by the upper parts of the latter. (See Fig. 13.) After the rifle is discharged the main breech-bolt is withdrawn, and by this the above-mentioned cam *p* moves the upper ends of the levers *o o*, and consequently also separates the upper parts of the pawls from each other. The cartridge No. 2 is pushed upward by the subsequent cartridges and into the chamber. During this ⁶⁵ operation the cartridge No. 3 is caught by the lower arms of the pawls and prevented from being further pushed forward, so as to arrive

on the further movement of the pawl entirely between the latter, and be held by the upper arms until the main breech-bolt is opened ⁷⁰ again. The motion of the pawls thus causes the cartridges to enter the chamber consecutively. In order to stop the repeating mechanism, stops of any description can be applied for pressing the lower parts of the levers *o o* together, (see Fig. 16,) so as to maintain the pawls in their position. (Shown in Fig. 14.) In this position of the levers *o o* the cam *p* of the closing head-piece *P* has no effect upon the levers *o o*, and the repeating mechanism ⁷⁵ is therefore disengaged. The pawls *m m* are of a peculiar construction, which is shown in Figs. 17 and 18. Each pawl consists of the pawl proper, *m'*, loose on the spindle *n*, and of an arm, *m²*, fixed to the spindle. The ⁸⁰ two parts *m'* and *m²* are connected together in one direction by a spring, *t*, and in the other direction by inserting *m²* into *m'*. The pawl *m* may turn, therefore, in one direction independently of the spindle *n*, and has to overcome only the pressure of the spring *t*. This construction is necessary in order to allow the magazine to be filled. The loading of the rifle takes place through the chamber when the supplemental breech-bolt is opened. For ⁸⁵ this purpose the cartridges are pressed between the pawls *m m*, which, in consequence of the above-described construction, yield and let the cartridges pass into the magazine. Even when the repeating device is disengaged, ⁹⁰ which position of the pawls is shown in Fig. 17, it will be possible to fill the magazine, as the lower arm of the pawl can be bent backward, owing to the arrangement of the spring *t*, this yielding permitting the cartridges to ⁹⁵ be introduced.

The improvements in the barrel of our new fire-arm consist in surrounding the same with a steel tube, *B*, in such a manner that an annular space is left throughout the whole length ¹⁰⁰ of the barrel between the barrel *A* and the steel tube, as shown in Fig. 1. The steel tube *B* is screwed to the fore end of the closing-socket, and by this means a solid connection is formed at this point between the barrel and ¹⁰⁵ the surrounding steel tube. The mouth of the barrel is loose in a casing, *g'*, which is soldered in or fixed by any other means to the fore end of the tube *B*. The sight of the fire-arm is placed on the exterior of the tube *B* ¹¹⁰ at *i*, and the tube is supported at this point by a ring, *h'*, placed in the interior of the tube and surrounding the barrel. This ring *h'* is provided with recesses *i' i'*, as shown in Fig. 2^a, so as to establish a communication between ¹¹⁵ the annular hollow spaces at both sides of the ring *h'*.

On the lower side the tube *B* is provided with a certain number of openings, *k' k' k'*, which are covered by caps *l' l' l'*.

The arrangement of the tube *B* has for its purpose (a) to prevent any soldering on the barrel; (b) to prevent any flexure of the barrel produced by external causes; (c) to avoid

all the inconveniences resulting from the connection of the wooden stock with the metal furniture. Such inconveniences are, for instance, the curving of the barrel heated by 5 firing, which curving results from the greater difficulty of the barrel to extend in the longitudinal direction; the intercepting and interrupting of the natural oscillations of the barrel in firing, and, finally, the curving of the 10 barrel produced by the warping of the wooden stock when this has become wet; (d) preventing, or at least reducing, the danger to which the person is exposed in case the barrel should burst by accident; (e) avoiding the 15 undulation of the hot air surrounding the barrel and heated by the same, which undulation renders aiming extremely difficult.

The openings $k' k' k'$, arranged on the lower side of the tube B, have for their purpose to 20 lead away the heated air and to cause the air to circulate. The caps $l' l' l'$ serve to prevent the rain from penetrating through the said openings. In lieu of the caps $l' l'$, any other suitable contrivance may be applied. It is 25 obvious that when necessary any number of rings i' may be employed to support the tube P. The casing may also be provided with recesses, like the ring i' , in order to produce a better circulation of air. It is very 30 essential in this construction that the tube B should be connected to the barrel A only at one end. If both the ends of the tube (i. e., the mouth of the tube also) be screwed to the barrel or secured to the same by any other 35 means, the barrel A would be curved in its middle part after having discharged a small number of shots, owing to the greater and more rapid extension of the barrel A in comparison with the tube B, which is not heated 40 at all, or only to a small extent. The last-mentioned circumstance renders this construction particularly fit for magazine-rifles, the barrels of which become heated after a short use to such an extent that the rifleman 45 cannot touch it with the naked hand.

Heretofore a cap has been attached to the tubular chamber of the breech-piece by means of a screw tapped into the end of the breech-piece; but this screw has no tappets.

Having now particularly described and ascertained the nature of this invention and in what manner the same is to be performed, we declare that what we claim is—

1. The combination, with the supplemental breech-bolt S, of the firing-pin a and a nut, b , secured to the end of the firing-pin, and having a flange lying against the end of the breech-bolt, said flange having lateral tappets $b' b'$, engaging the supplemental breech-bolt, substantially as shown and described.

2. The locking attachment consisting of a lever, $d e$, pivoted to the supplemental breech-bolt, one arm, d , of the said lever forming a handle, and the end of the other arm, e , having a cam which fits into a recess, e^2 , of the main breech-bolt V, so that by turning the

lever $d e$ the cam e^2 is pressed into a recess, e^2 , to lock the supplemental breech-bolt, substantially as described.

3. The combination, with the supplemental breech-bolt, of the handle c , having an annular or other similar form, the firing-pin, and a nut, b , tapped on the firing-pin, and having a flange lying against the end of the breech-bolt, said flange having tappets $b' b'$, engaging with the supplemental breech-bolt, and a detent-lever attached to the supplemental breech-bolt, for the purpose of cocking the same without opening the breech-bolt, substantially as shown and described. 70 75 80

4. The combination, with a curved magazine for containing the cartridges arranged in an oblique position and having their pointed ends turned upward, of a spring, h , and a follower, i , of the form shown, having a loose pivotal 85 connection at or about its middle portion with the spring h , substantially as shown and described.

5. In a magazine-gun, the combination, with the magazine-chamber M, of the coiled spring h , having an oblong form in cross-section, contracted at the central portions, and the follower i , pivotally connected to said spring at a point between the ends of said follower, substantially as described. 90 95

6. In combination with the gun-frame and breech-bolt, the head-piece P, having cams p , the levers $o o$, rigidly mounted on spindles $n n$ within the path of said cams, the pawls $m m$, mounted on said spindles over the rear end 100 of the magazine, and a feeding-spring acting upon the cartridges, substantially as described.

7. The combination, with the frame and breech-bolt, of the pawls $m m$, arranged in the 105 rear end of the magazine and rigidly mounted on spindles $n n$, the head-piece P, having cams p , the levers $o o$, rigidly mounted on said spindles and having their ends lying in the path of said cams, and stops pivotally mounted in proximity to said levers $o o$, whereby the latter may be locked in position to arrest the cartridges in their passage to the breech, substantially as described. 110

8. The combination, with the frame and 115 breech-bolt, the former having the magazine M, of the head-piece P, having cams p , the spring h , the compound pawls $m m$, each composed of the part $m' m^2$, the part m^2 being mounted on and turning with spindles $n n$, 120 and lying partly within the part m' , and a spring, t , whereby the part m^2 is normally thrown inward, substantially as described.

9. The combination, with the barrel A, of the tube B, surrounding said barrel, said tube 125 being rigidly connected at its rear end to the barrel, and having at its forward end a ring, g' , fastened within the mouth of the tube and loose upon the end of the barrel, substantially as described. 130

10. The combination, with the barrel A, of the inclosing-tube B, having the ring h' , hav-

ing bearing against both the tube and the barrel, and provided with openings i' , substantially as described.

11. The combination, with the barrel A, of the inclosing-tube B, having upon its underside openings k' , provided with protecting-caps l' , which overhang without closing said openings, substantially as described.

In testimony whereof we have signed our names to this specification in the presence of two subscribing witnesses.
